UNITED STATES PATENT OFFICE.

JOHN CALABRESE, OF WESTON, WEST VIRGINIA.

DOOR LOCK.

Application filed October 21, 1925. Serial No. 63,937.

The object of this invention is to provide a novel lock which will operate without springs, and a locksmith, working within the scope of what is claimed, can make 5 changes in the precise structure shown, without departing from the spirit of the invention.

Figure 1 is an elevation wherein the bolt is shown retracted; Figure 2 is an elevation 10 wherein the bolt is shown advanced; Figure 3 is a longitudinal section, the bolt being retracted; Figure 4 is a section on the line 4—4 of Figure 3; Figure 5 is a sectional detail which shows certain parts as they will 15 appear when the bolt has been shot; Figure 6 is a section on the line 6—6 of Figure 1; Figure 7 is a section on the line 7—7 of Figure 2; Figure 8 is a plan of the barrel; Figure 9 is an elevation of the barrel.

20 The lock includes a casing 1. There is a keyhole slot 41 (Figure 7) in the casing 1. At one end, the casing 1 has an opening 2. The casing 1 is provided with a transverse internal guide 3. A bolt 4 slides in the 25 opening 2 and in the guide 3. The bolt 4 has a circular opening 5. There are seats 6 in the upper edge of the bolt 4. A link 7 extends along one side of the bolt 4. The guide 3 is cut-away, as at 8, to receive the 30 link. The link 7 is pivoted at 9 to the bolt 4 to swing parallel to the bolt. The bolt 4 has right-line sliding movement in the opening 2 and in the guide 3. At its inner end, the link 7 is supplied with a circular opening 10. There is a seat 11 in the lower edge 35 of the bolt 4 below the inner end of the link 7.

40 A keeper block 12, of considerable weight, slides between the bolt 4 and one side wall of the casing 1 in a direction at right angles to the direction in which the bolt 4 slides. The keeper 12 is constrained to a right-line movement, because it has elongated slots 14 receiving pins 15 on the casing 1. Inwardly extended projections 16 45 on the keeper 12 overhang the bolt 4. When the bolt is shot, the projections 16 are received in the seats 6 of the bolt. A circular opening 17 extends part-way through the keeper 12. A thinned ward 18 projects 50 from the keeper 12 into the opening 17.

55 The numeral 20 marks a latch mounted to swing parallel to the keeper 12. One end of the latch 20 is pivoted at 22 to the lower end of the keeper 12. Near its opposite end, the latch 20 has an upstanding finger 21.

The finger 21 is adapted to be received in the seat 11 of the bolt 4, when the bolt is advanced. The latch 20 tilts on a fulcrum piece 23 carried by the bottom of the casing 1.

The lock includes a barrel 24 detailed in Figures 8 and 9. The barrel 24 is provided with a longitudinal keyhole slot 25. The barrel 24 has concentric circular ends 26. 65 The ends 26 of the barrel 24 are journaled in the side walls of the casing 1. A first eccentric 27 on the barrel 24 is received in the opening 10 of the link 7. The barrel 24 is supplied with a second eccentric 28. This 70 eccentric operates in the opening 17 of the keeper 12. There is a cross groove 29 in the barrel 24. The cross groove 29 receives the ward 18 on the keeper 12 when the barrel 24 is rotated.

75 The numeral 30 marks a key having a notch 31, a stop shoulder 32, and a beveled end 33.

80 When the bolt 4 is retracted, as in Figure 1, the keeper 12 is supported in raised position by the second eccentric 28 on the barrel 24. The projections 16 are out of engagement with the seats 6 of the bolt 4. The latch 21 is in the position of Figure 1, tilted downwardly toward its free end on the fulcrum piece 23, with the finger 21 of the latch out of engagement with the seat 11 in the bolt 4. The key 30 is inserted into the slot 41 of the casing 1 and into the slot 25 of the barrel 24. The barrel 24 is rotated, 85 and as it is rotated, the eccentric 27 on the barrel, cooperating with the link 7, advances the bolt 4. When the barrel 24 is rotated, the second eccentric 28 on the barrel moves around to the lower part of the opening 17 90 in the keeper 12. This permits the keeper 12 to move downwardly, and the projections 16 are received in the seat 6 of the bolt 4. When the keeper 12 moves downwardly, the latch 20 tilts on the fulcrum piece 23, and the finger 21 on the latch is received in the seat 11 of the bolt 4. The parts now appear 95 as depicted in Figure 2. The notch 31 in the key 30 permits the key to clear the ward 18 on the keeper 12, when the key is rotated 100 with the barrel 24.

105 Suppose that the parts are in the position shown in Figure 2. Then the key 30 may be slid into the slot 25 of the barrel 24, and the beveled end 33 of the key, cooperating 110 with the keeper 12, within the opening 17, raises the keeper. When the keeper 12 is

raised, the projections 16 are detached from the seats 6 in the bolt 4, and the latch 20 tilts on the fulcrum piece 23, so that the finger 21 of the latch is disengaged from 5 the seat 11 in the bolt 4. When the barrel 24 is rotated by the key 30, the eccentric 27 on the barrel, cooperating with the link 7, retracts the bolt, the second eccentric 28 coming around again into its uppermost 10 position within the opening 17 of the keeper 12 to support the keeper in the position shown in Figures 1 and 4.

The lock is devoid of springs, and in order to operate, it must be placed in the position 15 shown in Figures 1, 2 and 4, the part to which the reference character T is applied, in Figure 1, being considered the top of the lock, and the terms "upper", "lower" and the like, having been selected accordingly, in the 20 foregoing description.

I claim:—

1. A lock comprising a casing, a bolt 25 mounted for right-line sliding movement in the casing, a gravity-operated keeper mounted in the casing for substantially vertical right-line sliding movement in a direction about at right angles to the direction in which the bolt slides, a latch pivoted to the keeper and fulcrumed on the casing, the 30 latch having means for engaging the bolt when the bolt is advanced, and when the latch is tilted by the downward movement of the keeper, a key barrel journaled in the casing and having an eccentric cooperating 35 with the keeper to hold the keeper raised, when the bolt is retracted, the keeper comprising a part which cooperates with a key, when the key is inserted into the barrel, and when the bolt is advanced, to raise the 40 keeper; and mechanism for retracting the bolt when the barrel is rotated.

2. A lock comprising a casing, a bolt 45 mounted for right-line sliding movement in the casing and having a seat in its upper edge, a gravity-operated keeper mounted in the casing for substantially vertical right-line sliding movement in a direction about at right angles to the direction in which the bolt slides, a projection on the keeper, receivable in the seat to hold the bolt advanced, a key barrel journaled in the casing and having 50 an eccentric cooperating with the keeper to hold the keeper raised, and to keep the projection disengaged from the seat, when the bolt is retracted, the keeper comprising

a part which cooperates with a key, when the key is inserted into the barrel, and when the bolt is advanced, to raise the keeper and to disengage the projection from the seat; and mechanism for advancing and retracting the bolt when the barrel is rotated.

3. A lock comprising a casing, a bolt mounted for right-line sliding movement in the casing and having a seat in its upper edge, a keeper mounted in the casing 65 for substantially vertical right-line sliding movement in a direction about at right angles to the direction in which the bolt slides, a projection on the keeper, receivable in the seat, to hold the bolt advanced, a latch 70 pivoted to the keeper and fulcrumed on the casing, the latch having means for engaging the bolt when the bolt is advanced and when the latch is tilted by the downward movement of the keeper, a key barrel journaled 75 in the casing and having an eccentric cooperating with the keeper to hold the keeper raised, with the latch disengaged from the bolt, and with the projection disengaged from the seat, when the bolt is retracted, the 80 keeper comprising a part which cooperates with a key, when the key is inserted into the barrel, and when the bolt is advanced, to raise the keeper, to disengage the projection from the seat, and to disengage the latch 85 from the bolt; and mechanism for advancing and retracting the bolt when the barrel is rotated.

4. A device of the class described, constructed as set forth in claim 1, and further 90 characterized by the fact that said mechanism embodies another eccentric on the barrel, a link engaged with said eccentric, and means for pivoting the link to the bolt.

5. A device of the class described, constructed as set forth in claim 2, and further 95 characterized by the fact that said mechanism embodies another eccentric on the barrel, a link engaged with said eccentric, and means for pivoting the link to the bolt.

6. A device of the class described, constructed as set forth in claim 3, and further 100 characterized by the fact that said mechanism embodies another eccentric on the barrel, a link engaged with said eccentric, and 105 means for pivoting the link to the bolt.

In testimony that I claim the foregoing as my own, I have hereto affixed my signature.

JOHN CALABRESE.
